BEVEL GAUGE

Filed Oct. 9, 1929

UNITED STATES PATENT OFFICE

HAROLD AHOLA, OF STEVENSON, WASHINGTON

BEVEL GAUGE

Application filed October 9, 1929. Serial No. 398,370.

My present invention relates to an improved bevel gauge or mitering square for use by carpenters, joiners, and others, and especially those engaged in laying out angles 5 for cutting rafters, as in framing roofs of buildings. The gauge of my invention is of the straight edge type utilizing a pivoted, slideable, blade or ruler in combination with the straight edge, and employing duplex locking 10 or set means for rigidly joining the blade with the straight edge after the proper adjustment is found.

In carrying out my invention I utilize a scale or table plate, forming part of the 15 straight edge, upon which plate, scales, tables, graduations, and other data, appear, and both sides of the plate are utilized for this purpose. Both sides of the pivoted, slideable blade are also provided with data for use in laying off 20 marks and the duplex locking means are used at opposite sides of the instrument.

The invention consists in certain novel combinations and arrangements of parts as will 25 hereinafter, be more fully set forth and claimed. In the accompanying drawings I have illustrated one complete example of the physical embodiment of my invention wherein the parts are combined and arranged according to the best mode I have thus far devised for the practical application of the 30 principles of my invention.

Figure 1 is a plan view of the instrument embodying my invention, with the pivoted blade partly opened for convenience of illustration, and Figure 2 is a view of the reverse side of the instrument with the blade at a different angle.

Figure 3 is an edge view of the instrument as seen at line 3-3 of Figure 1. Figure 4 is 40 an enlarged sectional detail view at line 4-4 of Figure 1. Figure 5 is an edge view of the instrument. Figure 6 is a sectional detail view at line 6-6 of Figure 2. Figure 7 is a detail perspective view showing part of the slideable blade and also its pivoted washer. Figure 8 is a sectional detail view at line 8-8 45 of Figure 5.

I preferably form the straight edge 1 along the edge of a semi-circular plate 2 upon which 50 the scales, tables, tabulations, and other data

are affixed in suitable manner, and both sides of the plate are utilized for this data. The straight edge also extends along the edge of a handle portion 3 which is integral with and extends laterally from the circular plate. In 55 combination with the scale plate and its handle I also utilize a slotted plate 4 of which its slot 5 extends inwardly from the open outer end of this slotted plate. The plate 4 has a scale, reading in inches, along one edge of its 60 slot, and this scale indicates the distances from the end of the handle, and to be used as a depth gauge. By means of screws 6, at the slotted, outer end of this scale plate, the latter is rigidly secured to the outer end of the handle 3, and the scale plate is spaced from the handle and data plate to form a slot 7 for the reception of the pivoted, slideable blade or ruler 8 that is used to draw the lines of the 65 angles sought in cutting the rafters. 70

The pivoted, slotted blade is fashioned with a longitudinally extending slot 9 and upset flanges 10 are provided along the sides of the slot as best seen in Figure 8. The blade is slideable with relation to the data plate 2 and its 75 straight edge, and is also pivoted, a circular washer 11 being carried by the blade and fashioned with a central opening for the pivot screw 13. The washer is clamped stationary by means of a clamp nut 14 and its handle 15, 80 and of course the slotted blade or ruler is slideable with relation to its pivoted washer. The scale plate 4, as seen in Figure 1 is fashioned with a circular head 16 through which the pivot screw 13 passes, and the clamp nut 14 85 frictionally engages this head to hold the slotted blade 8 in adjusted angular position, with relation to the straight edge.

The angular marking position, of the ruler or blade is secured by means of a screw 17, 90 which is turned by its knurled head 18 and adapted to insert its smooth end into a selected socket or recess 19 of the data plate. These sockets are indented in both sides of the plate and they are located in predetermined positions on radial lines from the center pin or screw 13 of the instrument. In Figure 1 the sockets are shown in arcuate spaces between arcuate lines on the data plate, while in Figure 2 the sockets are shown on 100

lines radiating from the center or pivot pin and within segmental areas, and in both instances the sockets are located in predetermined positions with the necessary data and designations adjacent thereto for setting the blade 8.

The screw 17 thus becomes a setting pin that may be slid along in the longitudinal slot 9 of the blade 8, until the desired socket 10 is reached, and the desired angle of the blade is fixed by setting the pin in the socket, after which the parts are tightened by turning the handle of the lock nut.

The set screw is mounted in a slide nut 20, 15 under the flanges 10 of the slotted blade, and located between the blade and the data plate, and a guard 21 is secured at one end of the slide nut, and extends over the head 18 of the screw to prevent accidental turning or 20 placement of the screw.

When the instrument is used as indicated in Figure 2 and the blade is set in accord with the data on this face of the data plate, I employ an arm 22 that moves with the blade 8 and is jointed thereto at the outer end of the arm. The inner end of this arm 22 is pivoted on the center pin 13. At its outer end this arm has an angular, end post 23 of a width to slide freely in the slot 9 of the blade 8, or 30 rather to permit the blade to slide freely with relation to the arm, and a laterally extending head 24 on this post forms a T-shaped retaining head and guide. The post extends across the circular edge of the data plate, through 35 the slot 9, and the T-head is thus located at the outer side of the blade and on the side of the data plate opposite to the side where the slotted arm is located. The arm of course extends radially from the center of the instrument and is alined with the blade.

This arm has a longitudinally extending slot 25 alined with the slot 9 of the blade 8, and a set screw is movable along the slot, with a slide nut 26 in which the screw 27 is carried. 45 This screw is designed to co-act with a selected socket in one of the segmental areas of the data plate, and is used in manner similar to the set pin or screw 17, a guard 28 being used for the screw 27 similar to the guard 21 for the screw 17.

For measuring or gauging depths at which rafters are to be split, I use a slide gauge block 29 that is movable in the slot 5 of the plate 4, and this gauge block may be fixed in set position by means of a butterfly nut 30, after the distance has been determined by the scale along one side of the slot 5, the distance being determined from the free end of the handle 3.

Having thus fully described my invention, what I claim as new and desire to secure by Letters Patent is:-

1. In a measuring instrument of the straight edge type including a data-plate having sockets in its face, the combination

of a pivotal, slotted, slideable blade mounted on the data-plate, a slide carried by the blade, and a set screw mounted in said slide for co-action with a selected one of the sockets.

2. In a measuring instrument of the straight edge type including a semi-circular data-plate having sockets in its face, the combination with a slotted blade mounted on said plate and means for clamping the blade with relation to the plate, of a radially disposed arm pivoted on one side of the plate and having means for pivotal connection with the slotted blade on the other side of the plate, and adjustable setting means mounted on said radial arm for co-action with a selected one of the sockets.

3. The combination with an arcuate data-plate having sockets in its face, of a slotted blade pivoted at one side of the plate, a radial arm pivoted at the other side of the plate, said arm having a T-shaped guide post extending through and co-acting with the slotted blade, a slide carried by the arm, and a set screw in said slide for co-action with a selected one of the sockets.

In testimony whereof I affix my signature.

HAROLD AHOLA.
